UNITED STATES PATENT OFFICE.

EDWARD W. WILLIAMS, OF SAN FRANCISCO, CALIFORNIA.

MANTEL-GRATE.

SPECIFICATION forming part of Letters Patent No. 353,043, dated November 23, 1886.

Application filed January 23, 1886. Serial No. 189,547. (No model.)

To all whom it may concern:

Be it known that I, EDWARD W. WILLIAMS, a citizen of the United States, residing at San Francisco, in the county of San Francisco and State of California, have invented a new and useful Improvement in Mantel-Grates, of which the following is a specification, reference being had to the accompanying drawings, forming a part thereof.

10 This invention consists of a curved slotted lever connected to the grate and provided with a ball which operates upon a pin, and curved surfaces connected to the bottom of the basket, all of which will be hereinafter fully described.

15 In the accompanying drawings, Figure 1 is a plan of my mantel-grate. Fig. 2 is a view in section taken through the center of mantel-grate. Fig. 3 is a bottom plan view of the grate, its operating-lever, and the accompanying parts. Fig. 4 is a cross-section through the ball-and-socket joint at the inner extremity of the operating-lever.

20 A is the grate, pivoted within the grate-frame B and provided with means for end movement for shaking and dumping, as set forth and described in my application for a patent filed June 19, 1885, Serial No. 169,225.

To the under side of the grate are cast two lugs, C, the inner faces of which are made 30 slightly concave to receive the ball D at the end of the curved lever. Said ball D is conveniently supported between the curved surfaces by means of a horizontal transverse pin, D'.

35 The operating-lever E is slotted and curved upward, as shown, and operates upon a pin, F, the latter being supported by a right-angled lip, G, connected to the lower edge of the grate-basket, and the edges of both the right-angled lip and basket are rounded, so that the slotted and curved operating-lever will slide 40 freely without coming in contact with any sharp angles. The upper and lower faces of the ball at the end of the curved lever are slightly flattened for convenience in introducing 45 the ball to its socket, and this is accom-

plished by turning the ball flatwise, so that the flattened surfaces can be first introduced and then turned within the socket, in which position the rounded portions of the ball will 50 act in the concave portions of the lugs.

In practice it will be observed that by operating the lever to and fro the grate is shaken as well by this device as by my former invention hereinbefore mentioned, so that a shaking 55 as well as dumping grate is combined in one and the same device, and by pressing or bearing the curved lever downward by the projecting arm H the grate is quickly and easily dumped, the curvature of the lever being of 60 such an arc as to carry the grate backward toward the chimney or masonry of the fire-place beyond a perpendicular and effectually clearing the grate of all débris.

Having thus described my invention, what I 65 claim, and desire to secure by Letters Patent, is—

1. The combination of the grate-frame B, provided with lip G, having a pin, F, the dumping-grate A, pivoted in said frame and 70 provided with downwardly-extending lugs C C, whose opposing faces are concaved, and the curved and slotted operating-lever E, movable on the pin F and having a terminal ball, D, held between the lugs C, substantially as 75 described.

2. The combination, with the grate-frame B, having lip G, supporting the pin F, and the dumping-grate A, pivoted in said frame and provided with lugs C C, whose opposing faces 80 are concaved, of the curved and slotted lever E, movable on the pin F, and having a terminal ball flattened on the upper and lower sides and held between the lugs by a transverse rod, all arranged substantially as 85 described.

In testimony that I claim the foregoing I have hereunto set my hand and seal.

EDWARD W. WILLIAMS. [L. S.]

Witnesses:

C. W. M. SMITH,
CHAS. E. KELLY.
